UNITED STATES PATENT OFFICE.

EDWIN OPPENHEIMER, OF PHILADELPHIA, PENNSYLVANIA, ASSIGNOR TO EAGLE SUSPENDER & BELT CO. INC., OF PHILADELPHIA, PENNSYLVANIA, A CORPORATION OF PENNSYLVANIA.

DISPLAY CARTON.

Application filed July 22, 1921. Serial No. 436,887.

This invention relates to a display carton and package and more particularly to a package provided by a carton or container and an article contained therein; and has 5 special reference to the provision of a package of this nature in which the article is packaged to effectuate its preservation during marketing thereof, the package yielding an attractive display for purposes of 10 sale and affording the necessary inspection for purposes of purchase.

A prime desideratum of my present invention relates to the packaging and marketing of articles such as garment suspenders so 15 that the desired properties of the suspenders may be retained or preserved during the marketing thereof, the article being packed so as to afford an attractive display for purposes of sale, the package permitting 20 close examination or inspection of the style and quality of the suspenders prior to purchase. In prior methods of marketing garment suspenders the suspenders, whether sold "loose" or in cartons, were subjected 25 at the time of purchase to undesirable influences resulting from handling the same. When an assortment of suspenders were presented to a prospective purchaser for his 30 selection of style and quality the handling 35 of the loose article by the purchaser, who desired to examine and test their efficiency, resulted not only in soiling the article but in reducing the life of the same, exposing the suspenders to air, light and moisture and subjecting the same to the continual stretching 40 incident to testing the quality of the rubber, being factors in hastening the deterioration and reducing the life of the article. Where the article was sold in pack- 45 aged form, removal of the suspenders from its container was necessary wherever a close inspection as to the "make up" of the suspenders and nature of the materials used there- 50 in was desired by the customer, removal of the article subjecting it to the same undesirable influences resulting from handling. Such handling not only affected the life of 55 the article, exposure and stretching of the same rendering the same unfit for effective 60 subsequent display or sale, but such handling necessitated an undue consumption of time on the part of the distributor or 65 retailer in unpacking the article for presentation for sale and in replacing or repacking 70

the articles discarded by the purchaser, as 55 well as the article selected or purchased by him. It has therefore been found desirable to provide a suspender package in which the article and the distinctive portions thereof should be effectively displayed for purposes of sale, the article being subject to 60 close scrutiny and examination as regards its style and quality without the necessity of removing the suspenders from the carton provided therefor, the article being capable 65 of all the necessary inspection during marketing without breaking the package or affecting the identity thereof, preservation of the characteristics of the article not only being effectuated in this manner, but the 70 undue time wastage incident to packing and repacking of the article by the distributor or retailer being effectively eliminated.

The principal objects of my present invention therefore include, besides the provision of a display package having the characteristics and yielding the results above enumerated, the provision of a package in which the essential distinctive elements of the article, such as a pair of garment suspenders, are attractively presented to view; the further provision of a package in which the distinctive elements may be separately examined without affecting the integrity of the package and the provision of a package 80 in which the article is packed in a manner to permit the desired display and to permit removal of parts of the article for purposes of close examination without disturbing the identity of the package and the provision 85 of such a package in which the cost of packaging is a negligible quantity.

To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my invention and in which:

Figure 1 is a front elevational view of the package,

Figure 2 is a side elevational view in cross section and showing the manner in which the parts may be removed for close inspection, and

Figure 3 is a reduced view of a preferred

form of blank employed in the production of the packaged carton.

Referring to the drawings, the package comprises a carton or container and an article such as a pair of garment suspenders enclosed by the container, the container being provided with a front wall 10, a rear wall 11, opposed side walls 12 and 13 and opposite end walls 14 and 15, either or both of the said end walls 14 and 15 being adapted to be opened for insertion or removal of the article, the embodiment shown in the drawings contemplating both end walls 14 and 15 as adapted to be opened or closed. The front wall 10 of the carton is provided with cut out portions spaced longitudinally of the carton, the cut out portions defining display openings or windows 16 and 17 respectively. The windows 16 and 17 are intended for purposes of displaying the distinctive elements or features of the article enclosed by the carton, which, in the present form of my invention, comprises a pair of garment suspenders, the windows 16 and 17 being preferably open to permit the close examination and inspection of style and quality of the suspenders in a manner as will appear presently. The article packaged in the carton comprises, as hereinbefore mentioned, a pair of garment suspenders 18, the said suspenders being coiled or folded in a manner as clearly shown in Figure 2 of the drawings to provide a front lap or layer, the said front layer being provided to include the adjusting buckle 19, part of the resilient shoulder straps 20, the cast off 21 and the leather supporting straps 22, these comprising the distinctive elements of the garment suspenders. The suspenders when coiled or folded in this manner are inserted in the carton during the packaging step, with the front layer or lap of the suspenders lying adjacent to the front wall 10 of the carton, the adjusting buckles 19 and the resilient shoulder straps 20 being presented for display behind the opening or window 16, the cast offs 21 and the supporting straps 22 being presented for display between the window or opening 17 provided in the front wall of the carton. By folding the suspenders and packaging the same in the carton in this manner an attractive suspender display is presented, the style, color and character of the parts being thus open for attractive display and inspection.

For the purpose of securing a package in which the article held by the carton may be closely inspected without affecting the packaging of the article and without disturbing the condition of the package, the front wall 10 is provided with upper and lower ledge portions 23 and 24 and an intermediate transverse web portion 25, the openings 16 and 17 being so cut as to provide the ledge and web portions, such portions functioning to effectively retain the suspender elements in position, these portions, furthermore, permitting the individual suspender elements to be removed from the carton for purposes of close inspection without affecting the integrity of the package and of the packaged commodity. This is shown, for example, in Figure 2 of the drawings, wherein for purposes of illustration one of the resilient shoulder straps and one of the adjusting buckles are shown removed from the carton, the upper ledge 23 permitting such removal where the quality and properties of the suspender are desired to be scrutinized, the suspenders 18 being looped during packaging, as shown in Figure 2 of the drawings, as to permit the removal of a single front flexible loop of the suspenders for the desired examination. After inspection the removed parts may be reinserted in the package by introducing the same behind the said ledge 23. Similarly the cast off 21 and the supporting strap 22 may be also removed from the carton, ledge 24 being constructed to permit facility of removal of these parts, these parts being adapted for reinsertion in the carton behind the said ledge 24 after their inspection. The transverse web portion 25 during the removal and replacement of the distinctive elements of the suspenders effectively retains all the parts in properly folded position and in the carton, the cooperation of the ledge portions 23 and 24 and the transverse portion 25 with the looped or folded suspenders and the provision of the longitudinally spaced display windows thus permitting or affording any desired scrutiny or examination of the packaged commodity without breaking the package and without affecting the integrity of the packaged commodity, the identity of the entire package being preserved during marketing. Where a sale is consummated no further packaging step is necessary, the carton and the article contained therein being ready for simple wrapping operation.

For purposes of economy of manufacture the carton or container may be made from a single blank of material, as shown for example, in Figure 3 of the drawings, the said blank including the front wall portion 10, the rear wall portion 11, the intermediate portion 12 forming a side wall in the finished container, the side wing 13 forming the opposed end wall in the finished container and an oppositely arranged side flap 26 adapted to be adhesively secured to the wing 13 in forming the set up construction shown in Figure 1 of the drawings. The end walls 14 and 15 of the finished container are provided by the end laps 14 and 15, the said laps being, in turn, provided with flaps 14' and 15' respectively, the laps

and flaps defining removable end wall portions, as hereinbefore described. The blank may also be provided with a plurality of opposed flaps 12' and 13' adapted to be bent 6 and inserted beneath the end laps 14 and 15 in the setting up of the finished carton construction. The front wall 10 of the blank is cut out to provide the longitudinally spaced openings 16 and 17 hereinbefore referred to, 10 the ledge portions 23 and 24 and the intermediate web portion 25, as described in detail above.

The manner of packaging the garment suspenders and the manner of handling the package during marketing thereof will, in 15 the main, be apparent from the above detailed description thereof. The suspenders are preferably coiled or folded in a manner as shown in Figure 2 to provide for a freely 20 movable flexible front lap or loop including the main distinctive elements or features of the suspenders, these elements being capable of attractive display by the provision of the carton 10 and its spaced display windows 16 and 17, the distinctive elements of 25 the suspenders being capable of independent handling without exposure and soiling the entire article and without stretching or distorting the same and without affecting its 30 folded or looped formation, the identity of the package as a whole being retained and preserved during all conditions incident to the marketing of the product.

While I have shown my device in the preferred form, it will be obvious that many 35

changes and modifications may be made in the structure disclosed without departing from the spirit of the invention, defined in the following claims.

I claim:

1. A suspender package comprising a carton or container provided with a plurality of spaced display windows, top and bottom ledges and an intermediate transverse web, a garment suspender packaged by the container, the suspender being coiled or folded upon itself with the buckle adjacent an end fold, the latter being retained in position by one ledge or removable therefrom through one window to display the buckle portion 50 of the suspender and the other ledge and web retaining the remainder of the suspender in position.

2. A suspender package comprising a carton or container provided with a plurality of spaced display windows, top and bottom ledges and an intermediate transverse web, a garment suspender packaged by the container, the suspender being coiled or folded upon itself with the buckle adjacent 55 an end fold, the latter being retained in position by one ledge and the other ledge and web retaining the cast off and straps in position, the latter being removable from beneath the ledge through the window for display. 60 65

Signed at Philadelphia, in the county of Philadelphia and State of Pennsylvania, this 20th day of July, A. D. 1921.

EDWIN OPPENHEIMER.
